UNITED STATES PATENT OFFICE.

OSCAR ANDERSON, OF CROSBY, MINNESOTA.

FOLDING CHAIR.

Application filed February 19, 1925. Serial No. 10,251.

This invention relates to portable folding chairs adapted to be readily secured to a chair board or other horizontal member, and capable of being quickly collapsed into a structure adapted to be conveniently carried.

It is the main object of the invention to provide a simple but highly efficient folding chair of this nature, which may be readily set up for use or collapsed to be carried, equipped with a comfortable seat section and back rest.

A further object of the invention is to provide in such a device a folding resilient back adapted, when set up for use, to conform to the contour of the user and still be capable of being folded down substantially flat with the seat section of the chair.

It is a more specific object to construct the entire framework and back of the device from twisted resilient wire and nevertheless provide a construction which will be strong, durable and comfortable, though light in weight and occupying little space.

A still further object of the invention is to provide a portable folding chair having means integral with the frame thereof whereby the seat portion may be readily attached to the seat board of a rowboat, grandstand or ordinary flat bench. The invention is thus especially adapted for use by sportsmen and campers or football and baseball fans, where comfort, as well as the preservation of the clothing worn, is desired.

These and other objects of the invention will be apparent from the following description made in connection with the accompanying drawings wherein like characters refer to similar parts throughout the several views, and in which,

Fig. 1 is a vertical cross section taken through a rowboat with the preferred form of the invention mounted therein upon the usual transverse seat board;

Fig. 2 is a vertical section taken on the line 2—2 of Fig. 1;

Fig. 3 is a horizontal section taken on the line 3—3 of Fig. 1;

Fig. 4 is a plan view of the device in folded compact position;

Fig. 5 is a horizontal section taken on an enlarged scale showing the engagement of

the prop for the back section with the seat frame;

Fig. 6 is a detailed view on an enlarged scale showing the means for pivoting the back section to the seat section.

In Fig. 1 a flat bottomed rowboat is indicated by the numeral 7 having the usual transverse seat board 8 supported by the cleats 9. The preferred form of the invention illustrated comprises a substantially U-shaped frame 10 constructed from bent resilient wire having its outer ends bent inwardly to afford the resilient clips 11, said clips equipped with outwardly extending eyes or loops 11^a, the purposes of which will be later described. The frame 10 has also twisted therein a pair of aligned upstanding eyes 12, one at either side thereof, and a pair of spaced eyes 13 at the rear portion thereof. Within this frame 10 a seat pad 14, preferably of some soft material and of similar shape to said frame, is secured thereto in a suitable manner. Through eyes 13 projecting lugs or bolts 15 are passed and secured, the purpose of which will later be explained.

A spring skeleton back is provided comprising preferably a pair of substantially U-shaped members 16 constructed of resilient wire having their outer arms supplied with eyes 16^a adapted to be engaged by pivot members 17 passed therethrough and through the eyes 12 on the sides of said frame to pivotally secure the back section to said frame. The U-shaped members 16 are secured together by a member 18 extending therebetween and twisted about the inner arms thereof, forming, in cooperation with the extremities of said inner arms, notched portions 19 constituting a pair of props adapted to engage the projecting lugs 15 when said back section is swung back to normal operative position. Loops 20 are preferably bent in the U-shaped member 16 to afford a greater amount of resistance surface for the person using said chair. Loops 20 and the closed portions of U members 16 constitute back supporting means conforming approximately to the back of a person utilizing the chair.

The back section, obviously, may be folded against the seat section, the resiliency of the

wire construction permitting the outer arms thereof to be extended below and about the loops 11* to hold the device in compact collapsed position when so desired. The eyes 5 11* may also be used for positively securing the frame 10 to a horizontal member if desired.

The folding seat may obviously be quickly installed on a seat board of a rowboat or a 10 grandstand by slipping the clips 11 about the outer edges thereof and swinging the back section outwardly, simultaneously 15 springing the bracing members or props slightly backwardly and engaging the notched portions 19 thereof with the projecting lugs 15. When in such position, the back section of the seat will take a substantially horizontally curved position, thereby conforming to the contour of the back of a 20 person using said seat.

It will be obvious that sufficient resiliency will be embodied in the back section to afford a spring back for the user, supplying comfort as well as strength in the device.

25 From the foregoing description, it will be apparent that a useful and comfortable folding seat has been invented, capable of wide general use and adapted to be collapsed in a compact structure occupying little space.

30 The use of this device will prevent the soiling of clothes as well as provide a comfortable seat and back rest for a sportsman, camper, or football and baseball fan.

It will, of course, be understood that various 35 changes may be made in the form, de-

tails, proportions and arrangement of parts without departing from the scope of the invention.

What is claimed is:

1. A folding chair having in combination 40 a seat section and a spring skeleton back section, said back section comprising a pair of substantially U-shaped resilient wires having their outer legs pivoted intermediate the sides of said seat section, means for connecting the inner legs of said U-shaped wires together and means at the rear of said seat section for engaging the inner legs of said U-shaped wires, whereby said back section may be either collapsed flat against said seat 45 section or raised to upward position and the inner legs of said U-shaped wires may be sprung back behind said seat section and secured by said engaging means.

2. A folding chair having in combination, 50 a seat section, a spring skeleton back section, the sides of said back section being pivoted to the sides of said seat section adjacent the rear thereof, and lugs projecting from the sides of said seat section adjacent 55 the front thereof, said back section being capable of being collapsed flat against said seat section and the sides of said back section being adapted to be sprung down underneath said lugs to lock said back section in 60 collapsed condition against said seat section.

In testimony whereof I affix my signature.

OSCAR ANDERSON.
